PNEUMATIC THREAD HOLDER

Richard G. Turner, Worcester, Mass., assignor to
 Crompton & Knowles Loom Works, Worcester,
 Mass., a corporation of Massachusetts

Application March 23, 1942, Serial No. 435,875

7 Claims. (Cl. 139—247)

This invention relates to pneumatic thread holders for weft replenishing looms and it is the general object to provide means by which the thread holder is adapted for use with both coarse and fine yarns.

In my prior Patents Nos. 2,199,353 and 2,199,354 I have shown pneumatic thread holders for creating tension on the weft ends extending from reserve bobbins in a weft replenishing loom. As heretofore used the intake mouth of the thread holder has been of fixed cross-sectional area proportioned to operate with fine yarns. When coarse yarn is used in such a thread holder and the magazine is provided with a full complement of reserve bobbins the weft ends occupy so much of the intake mouth and air passage behind it that the small amount of air which can get through the unobstructed passage is insufficient for proper operation. As a result of this condition a thread holder which operates satisfactorily with small yarns will not operate successfully on large yarns. The reverse condition is also found to be true, namely, that if the thread holder is made sufficiently large to operate properly on large yarns there is uncertainty in its operation on small yarns due to reduced pressure caused by the large mouth. For successful operation there appears to be a rather limited range in the relation which the cross-sectional area of the thread receiving passage bears to the volume of yarns obstructing the passage. It is an important object of my present invention to provide means by which the effective cross-sectional area of the pneumatic thread receiving passage can be varied to accommodate the particular type of yarn being used in a magazine.

The pneumatic thread holder is generally used in connection with a thread accumulator located in such position as to cause the threads to extend along one side of the pneumatic passage. It is a further object of my present invention to provide the opposite side of the pneumatic passage with means by which the effective cross-sectional area of the passage may be varied. By this relationship the means employed to effect the adjustment does not interfere with the passage of threads along that part of the passage which they generally occupy.

With these and other objects in view which will appear as the description proceeds, my invention resides in the combination and arrangement of parts hereinafter described and set forth.

In the accompanying drawing, wherein a convenient embodiment of my invention is set forth.

Fig. 1 is an end elevation of a portion of a loom

having applied thereto a thread holder made according to my present invention.

Fig. 2 is an enlarged front elevation looking in the direction of arrow 2, Fig. 1.

Fig. 3 is a horizontal section on line 3—3 of Fig. 2.

Fig. 4 is an end elevation looking in the direction of arrow 4, Fig. 3 showing the thread holder being used with small diameter or fine yarns,

Fig. 5 is a vertical section on line 5—5 of Fig. 3,

Fig. 6 is a vertical section on line 6—6 of Fig. 3, and

Fig. 7 is a view similar to Fig. 4 but showing the thread holder associated with large diameter or coarse yarns.

Referring to the drawing, I have shown a loom frame 10 having a lay 11 which reciprocates backwardly and forwardly by means of a connector 12 driven by the top or crank shaft 13.

20 A pump cylinder 14 is secured to the frame and is provided with a piston 15 the connector 16 of which is attached to the upper end of a lever 17 pivoted at its lower end as at 18. An operating rod 19 connects the lever 17 to the lay 11 so that backward motion of the lay creates a partial vacuum in the left end of cylinder 14.

A supporting bracket 20 attached to the loom frame has mounted on the outer end thereof a thread holder base 21, from the left end of which as viewed in Fig. 3 extends a thread holder tube or the like designated at 22 having an intake mouth 23 which faces preferably toward the center of the loom. The base 21 receives the lower end of a cylinder 24 made preferably of transparent material. A cap 25 for the cylinder receives the forward end of a pneumatic tube 26 the rear end of which is connected as at 27 to the interior of the pump 14. A thread and air passage 30 extending through tube 22 connects the intake mouth 23 with the interior of the cylinder 24 and during backward motion of the lay the pump acts through the tube 26 to create a partial vacuum within the cylinder 24 to cause an inrush of air into the inlet mouth 23 and along the passage 30. The several threads which pass through the passage 30 become entangled in a thread mass designated generally at M located near the center of the cylinder 24. The threads are generally disposed as shown in Fig. 3, that is, they extend along the rear part of the passage 30.

The replenishing mechanism R comprises a magazine frame 35 which rocks on a fixed pivot 36 by means of a train of mechanism including link 37, lever 38 and a second link 39. The pivot 36 is mounted on a foot 40 which is secured to

the loom frame. Transfer mechanism T includes a transfer latch 42 normally below the path of a bunter 43 on the lay and pivoted to a transfer arm 44. The magazine is provided in the present instance with front and back stacks 45 and 46, respectively, of reserve bobbins from which extend weft ends W. It is these weft ends which extend to the intake mouth 23 and lie along the rear part of the passage 30 to be entangled with the thread mass M within the cylinder 24.

The matter thus far described of itself forms no part of my present invention and may be made as set forth in the aforesaid patents.

Depending upon the kind of fabric being woven in the loom the magazine may be provided with bobbins wound either with fine or coarse weft. When fine weft is employed it is desirable that the effective cross-sectional diameter of the passage 30 be relatively small so that sufficient draft will be created to suck the weft ends into the passage. When coarse yarns are used, however, it is desirable that the passage 30 be altered so that its effective cross section will be enlarged to prevent excessive obstruction by the coarse weft. In order to accommodate these conditions I provide the tube 22 with a forwardly extending hub 50 threaded at 51 to receive the threaded shank 52 of an adjusting screw 53 having a thumb head 54. The periphery of this head may be provided with a series of notches 55 for cooperation with a spring detent 56 secured as at 57 to the base 21. The rear part of the threaded shank of the screw is positioned to move across the passage 30. The latter is made amply large to operate successfully with coarse yarns when the screw is in its out or forward position so that the full cross section of the passage is available for both the yarn and the passage of air. When fine yarns are employed the screw is turned so as to move rearwardly and thereby reduce the effective cross-sectional area of the passage 30. The first of these conditions, that is with coarse yarns, is shown in Fig. 7 where it will be seen that the size of the yarn is such that a relatively large part of the passage 30 is obstructed making necessary movement of the screw to its forward position so that the unobstructed part of the passage will not offer too high resistance to the air column moving into the intake mouth. In Fig. 4 fine yarns are indicated as occupying only a small part of the passage 30, in which case the screw is moved to its rear position to reduce the area of the passage. The detent 56 will hold the screw in any of its adjusted positions, and the operator may turn the screw while the loom is in operation if necessary. This latter operation may be desirable when the coarse yarns are being used, since depletion of the number of bobbins in the magazine R will enlarge the unobstructed area of the passage 30, in which case the screw may be moved from the positions of Fig. 7 toward the positions of Fig. 4.

From the foregoing it will be seen that I have provided a simple means by which the effective cross-sectional area of the thread passage of a pneumatic thread holder may be varied to accommodate the size of weft being used. It will also be seen that the screw is on that side of the passage 30 opposite the side along which the weft ends W tend normally to lie as they pass from the intake mouth to the interior of the cylinder 24. It will further be seen that pro-

tection is made for holding the screw in any of its adjusted positions.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a group of reserve bobbins from which weft ends extend, a pneumatic thread holder having a passage therein to receive the weft ends, means to induce a draft of air into said passage away from the bobbins to attract the weft ends, and means movable laterally into said passage to assume a plurality of positions in said passage to effect a variation in the effective cross-sectional area of said passage.
2. In a weft replenishing loom having a group of reserve bobbins from which weft ends extend, a pneumatic thread holder having a passage therein to receive the weft ends, means to induce a draft of air into said passage away from the bobbins to attract the weft ends, and means movable into said passage laterally thereof by which the effective cross-sectional area of said passage may be diminished as the number of bobbins in said group is decreased.
3. In a weft replenishing loom having a group of reserve bobbins from which weft ends extend, a pneumatic thread holder having a passage therein to receive the weft ends, means to induce a draft of air into said passage away from the bobbins to attract the weft ends, said holder having a threaded bore communicating with the passage, and threaded means in said bore and movable therein to different positions in said passage to vary the effective cross-sectional area of said passage.
4. In a weft replenishing loom having a group of reserve bobbins from which weft ends extend, a pneumatic thread holder having a passage therein to receive the weft ends, means to induce a draft of air into said passage away from the bobbins to attract the weft ends, said holder having a threaded bore communicating with the passage, threaded means in said bore movable therein to different positions in said passage to vary the effective cross-sectional area of said passage, and means to hold said threaded means and prevent turning thereof with respect to said threaded bore.
5. In a weft replenishing loom having a group of reserve bobbins from which weft ends extend, a pneumatic thread holder having a passage therein to receive the weft ends, means to induce a draft of air into said passage away from the bobbins to attract the weft ends, said thread holder having a screw threaded bore therein communicating with the passage, a threaded member located within the bore and movable therealong to project different distances into said passage to vary the effective cross-sectional area of said passage, and a hand hold on said member by which the latter may be turned in said bore to vary the distance by which said member projects into said thread passage.
6. In a weft replenishing loom having a group of reserve bobbins from which weft ends extend into and along one side of the thread receiving passage of a pneumatic thread holder, means to induce a draft of air into said thread passage in a direction away from the bobbins, and means located at that side of said passage opposite said one side movable to different positions in said

passage to vary the effective cross-sectional area of said passage.

7. In a weft replenishing loom having a group of reserve bobbins from which weft ends extend into and along one side of the thread receiving passage of a pneumatic thread holder, means to induce a draft of air into said thread passage

in a direction away from the bobbins, means movable laterally with respect to said thread passage into the latter from the side thereof opposite said one side to vary the effective cross-sectional area of said passage.

RICHARD G. TURNER.
